Herbert Gayle ^{*Inventor.*}

UNITED STATES PATENT OFFICE.

HERBERT GAYLE, OF MONTGOMERY, ALABAMA.

DESIGN FOR A SPOON.

SPECIFICATION forming part of Design No. 27,162, dated June 8, 1897.

Application filed March 19, 1897. Serial No. 628,351. Term of patent 7 years.

To all whom it may concern:

Be it known that I, HERBERT GAYLE, a citizen of the United States, residing at Montgomery, in the county of Montgomery and State of Alabama, have invented and produced a new and original Design for a Souvenir Spoon, of which the following is a specification, reference being had to the accompanying drawing.

The leading or characteristic feature of my design consists in the handle portion of the spoon, which comprises a straight shank consisting of a series of connected swells or projections, each simulating a "buckeye," increasing in size regularly from the smallest, near the central portion of the handle, to the terminal or largest one, which is surmounted

by a crown, having upon its superior extremity a miniature bead or finial, also in the form of a buckeye. At the junction with the bowl the shank is widened out or expanded and swells up into a bead or knob of buckeye form. Within the bowl of the spoon, centrally disposed upon the surface thereof, is also a representation of the buckeye adapted to illustrate a suitable inscription.

What I claim, and desire to secure by Letters Patent of the United States, is—

The design for a souvenir spoon as shown and described.

HERBERT GAYLE.
